UNITED STATES PATENT OFFICE.

EDWARD G. HAYNE, OF OTTAWA, ILLINOIS.

LID-LIFTING DEVICE.

1,223,387.

Specification of Letters Patent. Patented Apr. 24, 1917.

Application filed March 28, 1916. Serial No. 87,360.

To all whom it may concern:

Be it known that I, EDWARD C. HAYNE, a citizen of the United States, residing at Ottawa, in the county of La Salle and State 5 of Illinois, have invented certain new and useful Improvements in Lid-Lifting Devices; and I do hereby declare the following to be a full, clear, and exact description of the invention, such as will enable others 10 skilled in the art to which it appertains to make and use the same.

My invention relates to new and useful improvements in lid lifting devices and more particularly to that class employed for lifting the lid or cover of a phonograph cabinet, and my object is to provide a pivoted beam, one end of which is attached to the lid or cover of the cabinet and the opposite end provided with a counter balance weight.

20 A further object is to so connect the weight and lid to the beam that the lid may be raised to any predetermined angle and be supported in its adjusted position by the weight.

25 A further object is to so equalize the weight of the lid with respect to the counter balance weight that the lid will not descend of its own volition.

30 And a further object is to provide means for operating the beam to raise and lower the lid.

Other objects and advantages will be hereinafter set forth and more particularly pointed out in the accompanying specification.

35 In the accompanying drawings which are made a part of this application,

Figure 1 is a side elevation of a phonograph cabinet showing the lid therefor in 40 elevated position.

Fig. 2 is a similar view thereof showing the upper portion of the wall of the cabinet broken away.

Fig. 3 is a front elevation of the cabinet 45 with the lid in elevated position, and

Fig. 4 is a side elevation of the cabinet showing a modified form of means for operating the beam.

Referring to the drawings in which similar reference numerals designate corresponding parts throughout the several views, 1 indicates a cabinet, which in this instance is shown as a phonograph cabinet, and 2 indicates the lid or cover for said cabinet, one 50 edge of which is attached to the upper end of the cabinet by means of a hinge 3.

As it is necessary to elevate the lid when a new record is placed in position or removed from the phonograph, considerable difficulty is frequently encountered in raising and lowering the lid as said lid is of considerable weight and unless extreme care is used the lid may drop and break the record or mash the fingers of the one raising the lid, and likewise the jar incident to the lid 60 striking the top of the cabinet frequently loosens the joints of the lid or cracks the coating or varnish thereon, thus spoiling the appearance of the cabinet, and to this end I provide means for elevating the lid without 65 necessitating the engagement of the hands with the lid comprising a beam 4, which is pivotally attached to a stud 5 secured to the inner face of the cabinet 1.

One end of the beam 4 is preferably bifurcated to form ears 6 between which is pivotally secured one end of a strap 7, the opposite end of the strap being pivotally secured between ears 8 of a bracket 9, said bracket being attached to the lid 2 in any 70 suitable manner adjacent the hinge edge of the lid. In order to equalize the weight of the lid whereby the same may be easily raised or lowered, a balance weight 10 is attached to the opposite end of the beam 4 from that 75 engaged with the strap 7, the size of the weight 10 being such as to equal the weight of the lid against the beam, so that the weight at both ends of the beam will be uniform, and it will be readily seen that the 80 lid may be raised or lowered with a minimum amount of exertion and that the lid will be held in its adjusted position until such time as the beam is operated to further raise or lower the same.

It will be understood of course that pressure may be directed against the lid to open or close the same but as the highly polished surface of the lid will become marred by finger prints remaining thereon, I prefer to employ a handle 11 for raising and lowering the lid, said handle projecting through a curved slot 12 in one wall of the cabinet, any suitable form of plate 13 being provided around said slot to protect the surface 100 of the cabinet against wear thereon and also to provide a suitable trimming around the slot. Instead, however, of providing the handle 11 for raising and lowering the lid, an elongated rod 14 may be attached to the 105 end of the beam 4 which projects downwardly through the bottom wall of the cabi-

net and has a head 15 which may be engaged with the foot for raising and lowering the lid, the rod 14 having an elongated counter weight 16 attached thereto which 5 equalizes the weight of the lid.

While I have shown the counter balance device as applied to use in connection with the lid of a phonograph cabinet, I desire it to be clearly understood that the same may 10 be used in connection with any device having a lid operated similar to the structure herein shown.

In operating the device it is but necessary to exert but a light upward or downward 15 pressure upon the handle 11 in order to swing the lid to a closed or open position and the lid may be moved to any suitable angle and held in such position by the counter balance weight, and in view of the equalization 20 of the weight of the lid at one end of the beam and the counter weight at the opposite end thereof, the lid will not move out of its adjusted position until pressure is employed for moving the same upwardly or 25 downwardly.

It will likewise be seen that by providing either the handle 11 or rod 14 the lid may be raised or lowered without touching the cabinet with the fingers, thus eliminating the 30 possibility of marring the varnish upon the cabinet or lid by finger marks, and as the lid gradually descends and pressure is applied to lower the same, the danger of in-

juring the lid by striking the top of the cabinet a blow is entirely eliminated.

It will likewise be seen that all of the parts except the operating handles are incased within the cabinet so that said parts will be excluded from view.

Having thus fully described my invention 40 what I claim as new and desire to secure by Letters Patent of the United States, is:—

The combination with a cabinet having a hinged lid thereon, of a beam pivotally attached to the inner face of the cabinet, a 45 strap pivoted at one end to one end of the beam and at its opposite end to the under face of the lid, a rod pivotally connected to the opposite end of the beam and projecting downwardly through the bottom of the cabinet, a counter balancing weight mounted upon said rod, and a head piece carried by the lower end of the rod whereby the lid may be opened or closed by the actuation of the head piece, said head piece adapted to 50 engage with the surface upon which the cabinet is mounted to limit the opening movement of the lid.

In testimony whereof I have signed my name to this specification in the presence of 60 two subscribing witnesses.

EDWARD G. HAYNE.
